UNITED STATES PATENT OFFICE.

ALLISTER S. MITCHELL, OF OAKLAND, CALIFORNIA, ASSIGNOR TO CALIFORNIA COTTON MILLS, OF OAKLAND, CALIFORNIA, A CORPORATION OF CALIFORNIA.

PADDING FOR SEAT BACKS.

Application filed May 31, 1922. Serial No. 564,705.

To all whom it may concern:

Be it known that I, ALLISTER S. MITCHELL, a citizen of the United States, residing at Oakland, in the county of Alameda and State of California, have invented certain new and useful Improvements in Padding for Seat Backs, of which the following is a specification.

My invention is an improved padding for 10 seat backs and particularly automobile seat backs.

The padding now used in the backs of automobile seats consists of a fibrous material which is sized on both surfaces, and 15 then hung upon racks to dry. This sizing and drying process consumes a considerable amount of time and labor. This sizing substance is starchy and greatly reduces the resiliency of the fibre. Before this padding can be inserted in the seat it must be cut into proper lengths, folded to the proper width, and then inserted. This entails a considerable waste of material and labor.

25 My padding is complete in one operation and is then the required width and length to be inserted into the seat, no further folding or cutting being necessary. Because of an interior reinforcing of the padding and 30 the absence of any sizing I can use a lighter weight and less expensive fibre than that which was formerly used. The tacks which hold the padding to the seat back have a firm hold in the reinforcing, and hold the padding in position.

Referring to the annexed drawing in which my invention is illustrated and which forms a part of this specification:

Figure 1 is a perspective view of an automobile seat and my pad illustrating how the 40 pad is introduced into the seat back.

Figure 2 is a plan view of my padding partly folded and secured with the remaining part flat and in position to be folded 45 and secured.

My padding consists of a sheet 1 of light weight fibrous material and a strip of paper 2. Said strip is laid centrally longitudinally on said fibrous material and both surfaces of said strip are covered with glue 50 or size. Both edges of the strip 2 are turned inwardly as at 3. This greatly strengthens the padding and prevents its separation while being inserted into the seats. The 55 fibrous material is folded longitudinally

over said strip and secured to the glued sides thereof, the edges of the material meeting on said strip, thus forming the padding. The padding is then introduced into the leather pockets 4 of the seat back as 60 illustrated in Figure 1.

By means of this structure I accomplish the following results: The labor cost required to make this padding is greatly reduced, due to shortening the time. After 65 the padding has been placed in the pockets it maintains its position and flexibility, the paper acting as a reinforcement. The pockets are filled uniformly since the padding is uniformly formed before inserting 70 and is then held in that shape by the paper strip.

While the invention has been illustrated and described as particularly applicable for use in stuffing the backs of automobile seats, 75 it is to be understood that the same is not limited to such use. It is equally applicable as padding for stuffed furniture of any kind and may be used also for packing purposes, particularly in covering articles 80 which are to be transported and which are liable to injury unless protected.

Having described my invention, I claim:

1. A seat back padding comprising a sheet of soft material, and a strip of material placed on said soft material and both sides glued, said soft material being folded over said strip of material and secured to the glued side thereof.

2. A seat back padding comprising a sheet of fibrous material, and a strip of paper glued along the center of said sheet, the edges of said sheet being folded inwardly and glued to the upper surface of 90 said strip.

3. A seat back padding comprising a sheet of fibrous material, a strip of paper glued along the center of said sheet, said paper strip having its edges turned over, the edges of said sheet being folded inwardly and glued to the upper surface of 95 said strip.

4. A protective device of the character set forth, a strip of fibrous material and a strip of reinforcing material enclosed by the 100 first mentioned strips and secured to the sides thereof by means of an adhesive.

5. A padding of the character described comprising a strip of paper, a strip of fibrous material enclosing said first named 110

strip so as to be secured to both sides thereof by means of an adhesive.

6. In a padding device, a strip of fibrous material, and a longitudinally disposed strip of paper glued centrally of said first strip, the edges of the fibrous strip being folded and overlying the strip of paper and adhering thereto.

7. In a protective device, a strip of paper having reinforced edges and a strip of fibrous material enclosing the strip of paper and adhering to both sides thereof.

In testimony whereof I affix my signature.

ALLISTER S. MITCHELL.
